UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed April 4, 1925. Serial No. 20,611.

My invention relates particularly to the construction and relative arrangement of the contact elements of a switch of that type having a pivoted switch member and a relatively stationary switch member.

The main object is to provide a construction which is reliable and uniform in its action.

Another object is to construct the parts so that the movement of the hinged or pivoted switch member is accomplished with a minimum of friction.

Another object is to provide a construction of the sliding butt type in which the current-carrying surfaces are well separated from the circuit-breaking points and in which the contact surfaces come together with a wiping movement rather than a rolling movement, as is usual in butt contact switches.

Another object is to provide a butt contact switch in which the thrust or pressure between the contacts is taken up by the pivot and the hinged member rather than against the operating means.

Another object is to provide an extended contact bearing under various conditions of assembly.

Another object is to provide a self adjusting, full and positive electric connection to the switch arm.

Fig. 1 is a side view of a switch embodying improvements of my invention, in the open circuit position but showing in dotted lines the closed circuit position of the contacts.

Fig. 2 is a sectional view of the hinged contact member on the plane of the line 2—2 of Fig. 1.

Fig. 3 is a side view and partial section on an enlarged scale showing the relatively stationary contact member.

Fig. 4 is a perspective view of the parts of the relatively stationary contact member shown separated.

Fig. 5 is a plan view and section on the plane of the line 5—5 of Fig. 3.

The member 7 of the switch preferably formed of two side plates or blades is hinged on the pivot pin 8 between the sides of the yoke 9 which is secured to the insulating base 10 in any suitable manner, as, for instance, by a screw 11. The contact end 12 is secured between the side plates of the

arm 7 in any suitable manner, as, for instance, by means of a rivet 13. In order to maintain a uniform frictional resistance to movement of the switch arm 7, I provide a spring 14 which is mounted on the rivet 8 and presses the side plates of the arm 7 out against the arms of the yoke 9. It is possible in this way to secure a practically constant pressure between the arm 7 and the yoke 9. A spring 15 is also preferably provided for the purpose of tending to open the switch or holding it in the position shown in Fig. 1. A sleeve 16 may be interposed between the springs 14 and 15 to prevent interference. The arm 7 is provided with shoulders 17 which co-operate with the upper ends of the yoke 9 so as to limit the opening movement of the switch arm 7 to the position shown in Fig. 1.

A relatively stationary element 18 is provided with a pin 19 which projects freely through an opening in the support 20 and has on it a spring 21 and washer 22 for holding it yieldingly in position. The support may be mounted in any suitable manner, as, for instance, by means of the screw 23. This contact has a circuit terminal 24. The lower edge of the contact member 18 is provided with a projecting boss 25. When the switch arm 7 is moved into the closed circuit position, it presses the contact 18 into the position shown in dotted lines in Fig. 1, the lug or boss 25 serving as the pivotal point. The spring 21, of course, exerts its pull on the contact 18 at a point between the boss 25 and the point of contact with the arm 7. This boss 25 being located in the approximate center in the lower edge of the contact 18, serves as a pivotal point about which the contact may twist side-ways to a slight extent so as to permit the contact to adapt itself to the shape and position of the tip 12 of the contact arm. This insures an extended line or surface of contact rather than a point contact which would occur if the member 18 were not permitted to twist. In order to provide an ample and perfect electrical connection between the contact 18 and the terminal 24, I may provide a flexible brush or strap connector 26 which may be formed of one or more layers of metal.

The contact tip is preferably rounded on the edge which strikes the contact 18 so that when the tip is leaving the contact 18 in the

act of opening the circuit the pressure of the contact 18 from its spring 21 will assist the main spring 15 in the opening movement.

5. When the switch is in the closed circuit position it will be noted that the contact 18 presses against the end 12 of the contact arm 7 in a direction which is substantially radial and therefore has no tendency to open the 10 circuit.

The movable switch member may, of course, be operated in any suitable manner. I have shown herein a thermostatic and toggle action mechanism which is the subject of 15 a co-pending application. The hinged operating member 27 is adapted to be operated manually and is connected to the switch arm 7 by toggle links 28 and 29, which are adapted to be automatically released by the warping 20 of a thermostatic element 30, which is connected between the circuit terminal 31 and the yoke 9. As switches of this type are intended to open the circuit automatically under predetermined conditions, it is highly 25 desirable that the resistance to movement remain substantially constant and unvarying. This particular construction of switch elements is, therefore, peculiarly adapted to such switches since the pressure of the contacts upon each other is invariable and the frictional resistance of the movable parts remain substantially constant.

I claim:

1. In an electric switch, a hinge post having spaced jaws, a pair of blades pivotally mounted on said post between said jaws, a spring located between said blades for pressing said blades into electrical engagement with said jaws, and a second spring surrounding the first spring for moving said blades.

2. In an electric switch, a substantially U-shaped supporting post having side jaws, a contact arm having blades mounted between said jaws, a pivot pin passing through said blades and jaws, a spring mounted on said pin and holding said blades in engagement with said jaws, a sleeve surrounding said spring, and a blade-operating spring 50 surrounding said sleeve.

3. In an electric switch, a bracket, an anchorage therefor, a contact arm, a spring holding said arm in engagement with said

bracket, said arm having a centrally-disposed boss engaging said bracket at all 55 times, the other end of said arm being adapted to be engaged by a movable switch member, said boss serving as the pivotal support for said arm when it is engaged by the switch member and permitting said arm to be tilted 60 in one direction and also permitting it to twist in a direction at substantially right angles thereto.

4. In an electric switch, a support having an opening, a contact arm having a contact 65 portion at one end and a boss at the center of its opposite end engaging said support, said arm also having an intermediate portion normally engaging said support, a pin connected to said arm and passing through the opening of said support, and a spring on said pin for pressing said arm into engagement 70 with said support, said arm being adapted to have a swinging movement with respect to said support and also a sidewise twisting 75 movement on said boss.

5. In an electric switch, stationary jaws, switch blades mounted between said jaws and spaced apart from each other, a rivet passing through said blades and jaws, a spring on said rivet between said blades, a contact member having a shank mounted between said blades, a rivet passing through said blades and shank for securing said contact member in place, and another rivet connecting said blades between the contact member and said pin.

6. In an electric switch, a hinged switch member, a support, a contact member having a centrally disposed boss engaging said support, a pin projecting through said support, and a spring mounted on said pin for yieldingly holding said contact in position but permitting it to tilt and twist when engaged by said contact member.

7. In an electrical switch, a pivoted switch blade and a contact to co-act with said blade, the said contact including a base member, a yielding switch contact member, a flexible conducting member for connecting said contact member with said base member, a rocking point support for said contact member and spring means for holding said contact member in engagement with said rocking point support.

BENJAMIN E. GETCHELL.
